UNITED STATES PATENT OFFICE.

SIDNEY A. KELLER, OF NEW YORK, N. Y., ASSIGNOR TO MARCUS T. GOLDSMITH, OF NEW YORK, N. Y.

DESIGN FOR A PURSE-TOP OR SIMILAR ARTICLE.

SPECIFICATION forming part of Design No. 35,747, dated February 18, 1902.

Application filed January 25, 1902. Serial No. 91,284. Term of patent 7 years.

To all whom it may concern:

Be it known that I, SIDNEY A. KELLER, a citizen of the United States, and a resident of the city of New York, borough of Manhattan, in the county and State of New York, have invented and produced a new and original Design for a Purse-Top or Similar Article, of which the following is a full, clear, and exact description.

Reference is to be had to the accompanying drawings, forming a part of this specification, in which similar characters of reference indicate corresponding parts in both views.

Figure 1 is a side view of a purse-top, showing my design; and Fig. 2 is an edge view of the same.

The design in its entirety consists in the approximately semicircular form of the lower margin and the outer edge, the space between the lower and outer edges appearing orna-

mented as complete flowers, the space between the margins also appearing with convex panels partly covered by some terminals of the floral pediment.

The leading feature of the design consists of an arch surmounted on the faces and outer margin by a complete floral pediment. 25

Having thus described my invention, I claim as new and desire to secure by Letters Patent—

The design for a purse-top or similar article, as herein shown and described. 30

In testimony whereof I have signed my name to this specification in the presence of two subscribing witnesses.

SIDNEY A. KELLER.

Witnesses:

THEO. G. HOSTER,
EVERARD BOLTON MARSHALL.
